SURFACE-TREATING MACHINE

Carl G. Wennerstrom, Evanston, Ill., assignor to
Universal Gear Corporation, Indianapolis, Ind.,
a corporation of Illinois

Application September 5, 1933, Serial No. 688,105

2 Claims. (Cl. 74—421)

This invention relates to surface-treating machines of the hand-controlled, motor-driven, rotary type, and its prime object is to improve the design, construction and operation of devices of that kind. It is shown and described herein as a floor-treating device, but without limitation to such particular use.

An important object also is to overcome the objection of grease leakage from the mechanism into the brush, sander, polisher, etc., or upon the floor or other surface being treated, which feature relates to the cup-shaped housing body which contains the immediate driving mechanism and carries the brush or analogous member. This same feature protects the operating mechanism from dirt, suds and water, and it also provides for adequate and constant lubrication since the cup-shaped member is adapted to hold a relatively large body of lubricating oil for the mechanism.

A further object is to provide a peculiarly sturdy and simple construction, of few parts, easily made and assembled, and which is noise-reducing and yet strong and durable and has indefinitely long life in service. Other objects and advantages will appear hereinafter or will readily be appreciated by those skilled in the art as resulting from the principles, or from the construction herein shown by way of exemplification of the principles, and which construction I now consider to be the best mode of carrying the invention into effect.

In the drawing Figure 1 is a side elevational view showing my improved machine complete, except for the operating handle which is indicated as being of the usual kind and is partly broken away, and which may be of any suitable form or even omitted in some uses of the device; Fig. 2 is a medial vertical fore-and-aft sectional view through the device, on an enlarged scale; and Fig. 3 is a fragmentary sectional view, on the line 3—3 of Fig. 2, showing readily-releasable interlocking means for the brush or other abrading or polishing member.

The driving motor 10 may be of any appropriate kind. It is mounted in and enclosed by the housing 11 having a bottom wall 11a through the flange of which extend bolts 12 holding the motor and its housing on the horizontal interiorly-open plate-like ring 14 which, in Fig. 2, is shown as having an interior thickened and downwardly-offset portion marked 14a. Current supply for the motor is had through the plug-in connector 15, and the motor is controllable by a

switch (not shown) in the hand of the operator in the usual way.

The bolts 12 also hold the open-bottom shell-like annular cover 17 rigid with the motor housing and ring 14, as shown in Fig. 2. This cover 17 adds to the appearance and serves as a shield for protecting objects above the floor from the brush or analogous member when in use. It is shown as a metal casting.

The motor shaft 20 has its lower bearing at 21 in the base 11a of the motor housing, and on the motor shaft is a pinion 23 rotating at motor speed. The motor shaft terminates at the bottom of pinion 23.

Motor pinion 23 meshes with a gear 24 which carries pinion 25, shown as being integral with gear 24, and these rotary toothed elements 24 and 25 rotate on the axis of the short vertical shaft 26. Conceiving the toothed elements 24 and 25 to be fixed rigidly to shaft 26 this shaft 20 has a bearing at 27 in extension 14a at the top and in a lug-like extension 28 at the bottom and which extension issues integrally from a tubular, downwardly-extending bearing support 29 which is held rigidly by the integral enlarged part 30 having sufficient circular length for the desired strength and is held by bolts 31 rigidly to the upper ring 14—14a. This supporting part 30 does not go all the way around, and is shown as terminating at 30a in Fig. 2, in order to provide clearance for the toothed elements 24 and 25.

It is thus seen that pinions and gears 23, 24, 25 have a bodily fixed relation to the motor housing, and that the framework 14, 14a secured to the motor housing and the framework 28, 29 and 30 (marked as a whole A) secured to parts 14, 14a provide a rigid support for the rotating toothed elements 24 and 25. I am emphasizing for clearness that gear 24 and pinion 25 do not revolve about the middle axis but always remain in the relative positions shown in Fig. 2.

The part that revolves and carries the circular brush is a cup-shaped member marked as a whole B and consists first of an annular ring 35 having an upper annular flange through which extends a plurality of bolts 36 holding a flat ring 37 which comes in close association with the vertical outer face of the annular, downwardly-projecting part 14a, as shown in Fig. 2, and to prevent oil leakage at this joint an annular gasket 38 is provided. The hollow interior of rotatable shell B is further enclosed by a flat sheet metal or fiber ring 39 held by the part 30 and bolts 31 and at its periphery accommodated loosely in an annular recess 39a in shell part 35.

Below the rotating annular part 35 is an integral reduced annular part 40, to the interior machined surface of which is rigidly secured the internally-toothed gear ring 41 which meshes with pinion 25. This outer rotatable housing extends thence inwardly by an annular horizontal flange-like part 42 to the downwardly-extending integral ring-like part 43.

The brush 44 is of the usual kind having a wooden disc-like base and brush elements extending downwardly therefrom. It has a central opening to accommodate the downwardly-projecting part 43 of the rotating cup-like member B which houses the gear mechanism. A laterally-extending lug 45 is integral with the extension part 43 and, as shown in Fig. 3, the base of the brush 44 is provided with a slot-like opening 46 which branches laterally at 46a and 47a to provide an inverted T-shaped recess accommodating the projection 45. The brush is applied by simply slipping it in place and giving it a short turn to lock projection 45 in a recess 46a or 47a. Ordinarily the motor will be driven in but one direction; but in the case of a reversible motor the brush would not come off, and on reversal would merely become locked in the other extension of the bayonet-slot recess. Any appropriate surface-contacting member, for example a disc having sandpaper thereon, or one having leather or fabric for polishing, or having other floor-treating elements, may be substituted for the typical brush shown.

Since the inner framework marked as a whole A is relatively fixed, and since the outer framework B is rotatable relative to it on its central axis, bearing means are provided between the members A and B. To this end, and as the more convenient means for manufacturing and assembling, I provide a construction for housing B that includes a removable closure in the form of a circular plate marked 50 in Fig. 2, and held by bolts 51 to the downwardly-extending part 43. An annular sealing washer 52 may be employed to insure against leakage of oil at this joint. Plate-like closure 50 has an upstanding hollow central stem 54 which is cylindrically machined externally to accommodate the inner rings a and c and the spacing ring 55 between them of a ball-bearing construction while the coaxial outer rings b and d and the spacing ring 56 fit against the machined inner surface of the extension 29 of fixed member A. These rings a and b at the top and c and d at the bottom provide raceways for the balls as shown. Means for holding the ball-bearing elements in place include an annular flange 57 at the top and a split locking ring 58 at the bottom for the outer ball-bearing elements, and there is a bolt 60 having a thin flat head 61 and washer 62 overlying the inner ball-bearing element a, and a nut 63 on the bolt clamping the inner ball-bearing elements and spacing ring 55 tightly to the central stem 54.

In assembling this ball-bearing mechanism we may begin by positioning bolt 60 and its washer 62 as shown in Fig. 2, the closure plate 50 and its stem 54 being removed. The several ball-bearing units and the spacing rings between them may be applied, the split locking ring 58 put in place, and then the closure 50 and its stem may be inserted, with the bolt 60 extending therethrough, and then nut 63 may be applied and also the bolts 51.

Briefly stated, the construction thus described 75 comprises an outer rotatable member which is

preferably cup-shaped and has a centrally-arranged upwardly-extending bearing member, and a rigid non-rotatable inner frame having a downwardly-extending bearing frame member, with bearing elements between these upwardly-extending and downwardly-extending frame members which are normally vertical and are preferably coaxial with the motor shaft axis, the outer rotatable frame member preferably being a non-leakable housing for the driving gears rotating on relatively fixed axes with respect to the motor and which communicate their driving power to the outer rotating member, with a brush or other appropriate surface-treating member held, preferably readily removably, on or at least 15 in driving relation to the cup-shaped member.

The main frame parts of the device are in my practice metal castings and are so shown. The gears may all be of metal, although if gear 24 and pinion 25 be of such material as "Micarta," 20 which is a well-known composition for gears, the operation of the gears will be characteristically smoother. The ball-bearing units may be of ordinary commercial kind. The device is illustrated substantially to scale as it is now being 25 made.

For convenience and simplicity I shall use the term "brush" in the appended claims to indicate either a typical brush, a sander, an abrader, a polisher or any other appropriate surface-contacting element that may be rotated by the mechanism for doing the work.

Various changes and departures may be made from what is thus specifically illustrated and described without departing from the invention, 35 and I contemplate all such variations, changes and departures as being included in the scope of the appended claims.

I claim:

1. In a surface-treating machine of the class 40 described, the combination with a motor frame for carrying a motor having a vertical shaft adapted to rotate on an axis concentric with said frame, of a deep rotatable cup-shape member rotatably supported beneath the frame, an opening at the bottom of said cup-shape member, a closure plate for said opening including a hollow upstanding stem integral with the closure plate projected into the interior of said cup-shape member, said frame having a bearing portion 45 extending downwardly within the cup-shape member and having a hollow downwardly-extending stem concentric with the first-mentioned stem and telescopically receiving the first-mentioned stem, a plurality of axially 50 spaced-apart annular anti-friction bearing members carried jointly by said stems, a bolt passing through the first-mentioned stem along said axis and cooperating to secure said anti-friction bearing members in position to maintain said cup-shape member and frame in rotatable relationship, and intermeshing gears carried within the cup-shape member jointly by said frame and cup-shape member for transmitting rotation of the shaft to the cup-shape member. 65

2. In a surface-treating machine of the class described, the combination with a motor housing carrying a motor having a vertically disposed shaft, of a deep hollow bearing member fixed to said housing to depend therefrom concentrically 70 with the motor shaft, said bearing member having a bearing portion at the lower end thereof, a pinion on the motor shaft received within said bearing member, a deep cup-shape rotatable member receiving said pinion and bearing mem- 75

ber, an internal gear on said rotatable member, a stub shaft carried jointly by said housing and bearing member, said stub shaft carrying one gear meshing with said pinion and another gear meshing with the said internal gear, the rotatable member having a central upstanding stem also concentric with said motor shaft and telescoping within the said bearing member, and

vertically spaced-apart annular anti-friction bearings between said stem and said bearing member, the said bearing member and rotatable member being of sufficient depth to accommodate the motor shaft pinion and the vertically aligned bearings in vertically spaced-apart alignment. 5
